UNITED STATES PATENT OFFICE.

WILLIAM A. BRUMAGE, OF MILWAUKEE, WISCONSIN.

ROD FOR CONNECTING SWITCH POINTS.

Application filed March 4, 1924. Serial No. 696,756.

To all whom it may concern:

Be it known that I, WILLIAM A. BRUMAGE, a citizen of the United States, and a resident of the city of Milwaukee, county of Milwaukee, and State of Wisconsin, have invented certain new and useful Improvements in Rods for Connecting Switch Points; and I do declare the following to be a clear, exact, and complete description thereof, such as will enable others skilled in the art to which the invention pertains to make and use the same, reference being had to the accompanying drawing for an illustration of the constructional features of my invention.

The invention relates to an improvement in the form of the rod or link which is used to connect the points of railway switches, and it is embodied in a construction in which an accurate adjustment of either or both of the said points may be made with respect to each other and to the rails with which they co-operate.

The device embodying my invention is of such construction that any desired adjustment in the parts indicated may be made with facility and without the necessity of removing from their fixed position any of the parts. As a consequence there will occur no interruption of the traffic on the railway by reason of any desired adjustments being made.

The novel features of the invention will be pointed out in the appended claims.

In the drawing:

Figure 1 is an inverted plan view of my improved connecting rod for the points of railway switches.

Fig. 2 is a partly sectional view of the same looking from the bottom of Fig. 1.

Fig. 3 is a plan view of section of a railway bed, showing my device in its operative position.

In the drawing, Fig. 3, the numeral 10 indicates the cross ties of a section of railway roadbed upon which are secured the usual main rails 11 over which the traffic is moved, all as will be understood. Where it is desired to install a switch, one of the main rails is made to diverge, as at 12 from its parallelism with the companion main rail, and the switch points 13 and 14 are arranged in the transverse line of such divergence. When in normal position with relation to the diverging traffic rail with which it co-operates, the switch point 13

constitutes the commencement of a continuance of the main traffic rail beyond the point of its association with such main rail. In such normal position, the point of rail 13 lies in parallelism with the companion main rail 11.

Near their ends, the switch points are connected by means of the composite rod shown in Figs. 1 and 2, such connection being effected through oppositely extending ears attached to the switch points near their ends. The composite connecting rod is formed of two aligned sections 16 and 17 which are threaded upon their outer ends and flattened upon their inner ends, the latter being perforated for the reception of bolts 18 passed through registering holes in plates 19 and 20, whereby the two sections 16 and 17 of the connecting rod are firmly united into a fixed, single structure. The plates 19 and 20 are insulated from the sections 16 and 17, and the perforations in the flattened ends of the latter are provided with insulating bushings, so that passage of electrical currents from one rail to the other will be prevented. It will be noted that the contiguous ends of sections 16 and 17 of the connecting rod are slightly separated from each other, to complete the insulation.

Turnbuckles 22 and 23 are screwed on the threaded ends of the sections 16 and 17, and connectors 24 and 25 having threaded shanks are screwed into the other and outer ends of the turnbuckles. Inside jam nuts 26 are upon the threaded sections 16 and 17 are adapted to engage the turnbuckles at inner end, while outside jam nuts 27, threaded upon the shanks of the connectors 24 and 25 are adapted to engage the outer ends of the turnbuckles.

The connectors 24 and 25 are forked at their extreme ends, as shown, and are bored through from top to bottom as at 28 and 29 for the reception of a pin which is passed through an eye in the ears upon the inside of the switch points as has been described.

The plate 19 is provided with a projection 30, perforated near its end, and which in actual practice will extend into a plane below that of the cross ties for the accommodation of the connecting link 31 which forms the locking rod, as is well known, and by means of which the switch points are held positively in one or the other of the positions to which they have been moved, so that the flanges of the wheels of the railway car in

running against the switch points cannot disturb the relation which they occupy with reference to the traffic rails.

The several means for adjustment which I have provided will enable any necessary or desirable adjustment to be made with the utmost ease and the greatest precision, and without in any way disturbing the connection when it once has been made. The per-
10 forated projection 30 may occupy a mean position which usually will be preserved, irrespective of any adjustment of the switch points which may be found necessary. The connecting rod can be lengthened or short-
15 ened without disturbing the position of the projection 30, and the adjustment of one switch point without reference to the other can be made. In effecting the desired ad-
justment, it is necessary only to loosen the
20 jam nuts 26 and 27 at the opposite ends of the turnbuckles, so that the latter may be turned by the application of a wrench to lengthen or shorten the section of the con-
necting rod. When the adjustment desired
25 has been made the jam nuts are again set in position against the ends of the turn-
buckles. The construction and arrangement
30 are such that the adjusting elements are easily accessible, so that the only tool re-
quired for use by the inspector will be the open end wrench which will receive both the jam nuts and the turnbuckle. While I have
35 shown the projection 30 as extending in a plane which is normal to that of the plate
19 it is obvious that the projection need not be so arranged but will have such disposition upon the plate 19 as will enable the switch point locking rod 31 to be conveniently coupled thereto.

40 Having thus described my invention, what I claim and desire to secure by Letters Patent of the United States is:

1. A composite connecting rod for the switch points of a railway track, such rod comprising two aligned connecting sections insulated from each other at their con-
45 tiguous ends and threaded upon their outer ends, turnbuckles upon such threaded ends, and connectors in the opposite ends of the
50 turnbuckles for connection to the switch points.

2. A composite connecting rod for the switch points of a railway track, such rod comprising two threaded sections flattened

55 at their contiguous ends, plates secured thereto to hold such ends in alignment and insulated therefrom, outer ends of the aligned sections being threaded, turnbuckles thereon, and connectors threaded into the outer ends of the turnbuckles and forked for
60 connection to the switch points.

3. A composite connecting rod for the switch points of a railway track, such rod comprising two sections threaded at their outer ends and connected at their inner ends
65 by plates insulated therefrom, one of the said plates having a projection thereon for attachment of the switch point locking rod, turnbuckles threaded upon the outer ends of the sections, and connectors threaded into the opposite ends of the turnbuckles, the said connectors being perforated at their extreme ends for attachment to the switch points.

4. A composite rod for connecting the switch points of a railway track, the said
70 rod comprising two aligned sections, means for connecting the sections, turnbuckles threaded upon the outer ends of the sections, and connectors for the switch points threaded into the opposite ends of the turn-
75 buckles.

5. A composite connecting rod for the switch points of a railway track, the said rod comprising two sections threaded at their outer ends, threaded connectors to the
80 switch points, and turnbuckles intermediate the connectors and the threaded sections, whereby either connector may be adjusted without disturbing the other.

6. In a composite connecting rod for the
85 switch points of a railway track, the said rod comprising two sections aligned and united at their contiguous ends, connecting means for the locking rod upon such align-
90 ing and uniting means, connectors for at-
taching the rod to the switch points, and turnbuckles for connecting the said connec-
95 tors and the aligned sections, whereby either connector may be adjusted without disturb-
100 ing the other or the connection with the locking rod.

In testimony of which I have signed my name at Milwaukee this 23d day of February, 1924.

W. A. BRUMAGE,
